UNITED STATES PATENT OFFICE.

JOHN WILSON, OF NEW YORK, AND ALLAN MASON, OF BROOKLYN, ASSIGNEES TO HERBERT H. SANDERSON, TRUSTEE, OF NEW YORK, N. Y.

HYDROCARBON-BURNER.

SPECIFICATION forming part of Letters Patent No. 438,514, dated October 14, 1890.

Application filed June 8, 1888. Renewed March 26, 1890. Serial No. 345,626. (No model.)

To all whom it may concern:

Be it known that we, JOHN WILSON and ALLAN MASON, citizens of the United States, and residents of New York city, in the county 5 and State of New York, and Brooklyn, Kings county, New York, respectively, have invented certain new and useful Improvements in Hydrocarbon-Burners, of which the following is a specification.

10 Our invention is an improved contrivance of hydrocarbon-injector burners for regulating the oil-supply in marine-boiler furnaces, where the rolling of the ship causes irregularity of the flow in the feed-pipe, all as hereinafter fully described, reference being made 15 to the accompanying drawings, in which—

Figure 1 represents a sectional elevation of our improved injector, as when the ship is in the normal position. Fig. 2 is a section of the 20 oil-feed regulator, as when the ship is in the same position. Fig. 3 is a section of the regulator, as when the injector has a descending inclination by the roll of the ship. Fig. 4 is a section of the regulator, as when the injector 25 has an upward inclination by the roll of the ship, and Fig. 5 is a sectional elevation of a marine boiler having our improved burner applied to it.

The oil, steam, and air are mixed or combined in a mixing-chamber or casing *a* prior 30 to entering the furnace, said mixing-chamber consisting of the tube inserted about midway of its length or a little more in the fire-door or furnace-plate *m*, and having its ends open 35 and curved upwardly; also, having the oil-feed pipe *b* discharging into it through the bottom and outside of the furnace, and also having the steam-nozzle *d* introduced a certain distance from the outer end, as shown, whereby 40 the oil from the oil-feed pipe *b* is combined with the air entering the chamber at *c* by the effect of the steam-jet from the nozzle *d* for combustion at the issue *e* in the furnace-chamber. This mixing-chamber stands level 45 when the ship is level; but by the rolling of the ship it sometimes has a downward pitch, as in Fig. 3, which accelerates the flow of the oil and causes an over-supply, and at other times it has an upward pitch, as in Fig. 4, 50 which retards the flow and prevents the supply of the requisite quantity at the burner,

while the steam-jet and air injected by it continue the same, thus materially interfering with effective and economical combustion.

To remedy this evil we provide the oil-feed pipe with a regulating-cock *f*, having a pendulum regulator *g* for automatically shifting it, which cock and pendulum are so adjusted that they partly close the passage *h* to regulate the supply when the mixing-chamber stands level, as in Figs. 1 and 2, and close it still more when the pitch of the chamber is downward, as in Fig. 3, but open it wider when the pitch is upward, as in Fig. 4, thus effecting automatic regulation according as 65 the ship rolls.

The chamber is constructed with an upward curve of the outer end to prevent the outflow of any oil that may possibly fail of being drawn inward by the suction of the jet 70 when the pitch of the injector is upward, and the inner end is also made with an upward turn as a further means of limiting the flow when the pitch is downward, and also with cross-ribs or bars *i*, and pockets *j*, along the 75 bottom of the interior for the lodgment of any unvaporized portions for obstruction and retention till effectually broken into spray by the jet. The bottom is also perforated with numerous small orifices *k* along the curve and 80 between the cross-ribs for a further means of causing the scattering of the atoms in spray, and for the issue in divisional jets into the atmosphere of the place of combustion.

m represents the door or front plate of the 85 furnace, through which the injector is inserted.

What we claim, and desire to secure by Letters Patent, is—

1. The combination, with the furnace-chamber, of the mixing-chamber having both ends 90 open and upwardly curved to prevent outflow of oil when out of level by the pitch of the vessel, and extending into the furnace-chamber through the front of the same, the oil-supply pipe connected with said mixing-chamber, and the steam-jet pipe entering said 95 outwardly-curved open end and projecting the steam against the inner surface of the upwardly-curved bottom of the inner end of said mixing-chamber, substantially as described.

2. The combination, with the furnace-cham-

ber, of the mixing-chamber, having both ends open and upwardly curved to prevent the outflow of oil when out of level by the pitch of the vessel, and extending into the furnace-chamber through the front of the same, the oil-supply pipe connected with said mixing-chamber, the regulating-cock in the oil-pipe, the pendulum actuator of the regulating-cock, and the steam-nozzle inserted in the outer open end of the mixing-chamber, and projecting the steam against the inner surface of the upwardly-curved bottom of the inner end of said mixing-chamber, substantially as described.

15 3. The combination, with the furnace-chamber, of the mixing-chamber having both ends open and upwardly curved to prevent outflow of oil when out of level by the pitch of the

vessel, and extending into the furnace-chamber through the front of the same, the cross-²⁰ ribs, pockets, and perforations in the bottom of the inner upwardly-inclined end, the oil-supply pipe connected with the mixing-chamber, and the steam-injecting nozzle projecting the steam upon the bottom of the said upwardly-inclined inner end of the mixing-chamber, substantially as described.

Signed at New York city, in the county of New York and State of New York, this 12th day of April, A. D. 1888

JOHN WILSON.
ALLAN MASON.
